PULL

John R. Morgan, Northbrook, Ill., assignor to Amerock
Corporation, Rockford, Ill., a corporation of Illinois

Application April 4, 1957, Serial No. 45,592

Term of patent 14 years

(Cl. D10—8)

Fig. 1 is a front elevation of a pull showing my new design.

Fig. 2 is a side view.

Fig. 3 is a sectional view taken along the line 3—3 in Fig. 1.

Fig. 4 is a sectional view taken along the line 4—4 in Fig. 2.

Fig. 5 is a sectional view taken along the line 5—5 in Fig. 2.

I claim:

The ornamental design for a pull, substantially as shown.
